UNITED STATES PATENT OFFICE.

ELI PRATT, OF BAY CITY, MICHIGAN, ASSIGNOR OF ONE-HALF TO OLIVER DUQUETTE,
OF BAY CITY, MICHIGAN.

CURTAIN-POLE-SUPPORTING ATTACHMENT.

1,165,625.

Specification of Letters Patent. Patented Dec. 28, 1915.

Application filed March 13, 1915. Serial No. 14,208.

To all whom it may concern:

Be it known that I, ELI PRATT, a citizen of the United States, residing at Bay City, in the county of Bay and State of Michigan, have invented certain new and useful Improvements in Curtain-Pole-Supporting Attachments, of which the following is a specification, reference being had to the accompanying drawings.

10 My invention relates to devices for supporting curtain poles, and particularly to an attachment adapted to be applied to an ordinary shade bracket and adapted to support a curtain pole in connection therewith.

15 The primary object of my invention is to provide a very simple device so constructed that it may be readily applied to and engage with an ordinary roller shade bracket, and which when in place will support the curtain pole from which lace curtains usually hang.

20 A further object of the invention is to so form this device that it may be cheaply and simply made and may be sold at a very small cost.

25 My invention is illustrated in the accompanying drawings, wherein—

Figure 1 is a top plan view of a shade roller and bracket arms therefor with my attachment engaged with the brackets; Fig. 2 is a side elevation of the construction shown in Fig. 1; Fig. 3 is a section on the line 3—3 of Fig. 2; Fig. 4 is a perspective view of the curtain pole detached.

Referring to these drawings, it will be seen that my attachment consists of a length of wire 2 angularly bent to provide arms 3 and 4 extending at right angles to each other, these arms when in position upon the bracket being disposed in a horizontal plane. The 35 arm 3 at its outer end is bent as at 5 to form a curved seat for the end of the curtain pole, while the arm 4 at its extremity is bent upward then at right angles as at 6, this portion 6 being also at right angles to the plane of the members 3 and 4, and the 40 extremity of this portion 6 is inwardly bent as at 7 and then downwardly bent as at 8.

In use the device is applied as follows:

As illustrated in Fig. 1, the device is adapted 50 to be applied to an ordinary shade roller

bracket which is designated A, this shade roller bracket being attached to the window casing B. These shade roller brackets have seats or bearings at their extremities for the reception of the usual shade roller C, and 55 also each of these shade roller brackets is usually formed intermediate the base of the bracket and the bearing for the shade roller with a perforation a. The portion 8 of my attachment is intended to be inserted 60 through this opening from the inside face of the bracket so that the upper wall of the perforation a will bear against the bend 7 while the portion 6 will extend upward upon the inner face of the bracket and will bear at 65 its upper end upon the upper edge of the bracket, the portion 4 thus extending downward at right angles to the bracket.

I have found in practice that this device is entirely effective in supporting the curtain 70 pole, inasmuch as the portions 6, 7 and 8 can not rotate upon the bracket A, the device being held from rotation upon the bracket A by the bend at the juncture of the portions 6 and 4. 75

It is obvious that my device may be very cheaply made and sold at a very low cost and is very easily applied. It will of course be obvious that these supporting members may be formed in a more or less ornamental 80 shape, and I therefore do not wish to be limited to the exact design illustrated.

Having described my invention, what I claim is:

The combination with a shade roller 85 bracket having a perforation formed in its body portion; of a curtain pole support co-acting therewith, said support consisting of a length of material bent to provide arms in right angular relation to each other, one 90 arm extending toward the bracket, the second arm being disposed in parallelism with the bracket and positioned outwardly therefrom, the extremity of said second arm terminating in advance of the outer extremity 95 of the bracket and being provided with a curtain pole seat, the first named arm at its inner end being upwardly deflected to bear upon the upper edge of the bracket and then 100 downwardly bent, the intermediate part of

the downwardly disposed portion being laterally deflected, said downwardly disposed portion being insertible through the opening in the curtain pole bracket whereby engagement is had with the opposite faces of the bracket.

Copies of this patent may be obtained for five cents each, by addressing the "Commissioner of Patents,
Washington, D. C."

In testimony whereof I hereunto affix my
signature in the presence of two witnesses.

ELI PRATT.
